UNITED STATES PATENT OFFICE.

KARL MAIER, OF STUTTGART, GERMANY, ASSIGNOR TO UNION SPECIAL MASCHINEN-FABRIK, G. M. B. H., OF STUTTGART, GERMANY.

SEWING AND EDGING MACHINE.

Application filed August 3, 1926, Serial No. 126,844, and in Germany August 24, 1925.

The invention relates to new and useful improvements in sewing machines, and more particularly to a sewing machine of the type shown in the United States Patent No. 5 1,266,884, granted R. B. Thompson, May 21, 1918. The above machine is adapted for forming and stitching an edging to the edge of a body material, and includes vibrated needles which are spaced from each other, 10 a tape guide for directing the tape between the needles, and thread laying fingers for laying an edging thread above and below the tape so that the stitching threads join the edging threads together, and also join 15 the edging threads to the body fabric.

An object of the present invention is to provide a machine of the above type wherein in the path of travel of the thread laying fingers which form the edging is capable of 20 adjustment so that said path of travel may be properly disposed relative to the needles.

A further object of the invention is to provide a thread controlling device for the thread laying fingers which form the edging, 25 which is shiftable with the shifting of the oscillating position of the thread fingers, so that for all adjustments of the thread fingers, a uniform thread control on the edging threads may be obtained.

30 These and other objects will in part be obvious and will in part be hereinafter more fully disclosed.

In the drawings which show by way of illustration one embodiment of the invention—

Figure 1 is a front view of a machine embodying the improvements, certain of the parts being omitted for the sake of clearness;

Fig. 2 is a view from the rear of the machine of the parts adjacent the needle head, 40 many of the parts being omitted for the sake of clearness, and many of the parts being shown only diagrammatically;

Fig. 3 is a view, more or less diagrammatic, showing the means for supporting the thread laying fingers, which form the edging, the view being taken from the front of the machine;

Fig. 4 is a similar view from the rear side 50 of the machine.

Fig. 5 is a view partly in plan and partly in section, showing the bracket for support-

ing the thread laying fingers, and also showing the thread control for the thread laying fingers;

55

Fig. 6 is a view partly in section and partly in plan of the main parts shown in Fig. 5, and showing in broken lines the adjustment of the support for the thread laying fingers;

Fig. 7 is a sectional view on the line 2—2 60 of Fig. 6;

Fig. 8 is a plan view showing the thread laying devices, the support therefor, and the thread controller for said thread laying devices, said thread laying devices being shown 65 in full lines in the intermediate position and in dot and dash lines in the most forward and the most rearward positions of the thread laying devices, and also showing in dot and dash lines the movement of the 70 thread controlling device, and

Fig. 9 is a plan view on an enlarged scale showing the thread laying fingers which form the edging and the supporting bracket therefor, also showing in full lines the 75 stitches formed by the needles, and showing in dot and dash lines a different setting of the needles and the shifted position of the thread laying fingers.

The invention is directed to a machine 80 for forming an edging on a body fabric of the type shown in the Thompson patent above referred to. In this patent, there are two needles carried by a needle bar which is mounted in a needle gate, which needle gate 85 in turn is vibrated laterally, so that the needles form two independent rows of zig-zag stitches. Suitable complementary stitch forming devices cooperate with the needles beneath the material. A tape is 90

guided by a suitable tape guide between the needles. Thread laying fingers are provided which oscillate back and forth in front of the needles, one of said thread laying fingers moving above the tape and the other 95 below the tape. These thread laying fingers operate only at intervals as compared with the formation of the zigzag stitches, and the needle threads join the loops formed by the edge forming fingers to the body fabric and

100 to each other, one needle operating at one side of the tape and the other operating at the other side of the tape. There are other features in the Thompson machine referred

to, but it will not be necessary to refer more in detail to them in order to understand the present invention.

The present invention is directed particularly to the mounting of the thread laying fingers. These thread laying fingers swing about a pivotal center on a bracket carried by the head of the machine. According to the present invention, this bracket is made in two parts, and one is adjustable relative to the other for shifting the center of oscillation of the thread laying fingers. The shaping of the parts is such that when the needles are set comparatively close together or at considerable distance apart in the setting up of the machine, then the center of oscillation of the thread laying fingers can be shifted so as to maintain a predetermined distance between the paths of movement of the thread laying fingers and the needles. This enables the machine to be readily set up and adjusted for inserting the desired width of tape. Another feature of the present invention is the thread controlling device for the threads of the thread laying fingers. This is a yielding device, and is mounted on the shiftable part which supports the thread fingers, so that when the thread fingers are shifted, the thread control will be likewise shifted and always maintain the same position relative thereto.

Referring more in detail to the drawings, the present improvement is shown as applied to a machine including a base 1 having an overhanging arm 3. Mounted to oscillate on the overhanging arm is a needle lever 7 which reciprocates a needle bar 6. This needle bar 6 carries two needles 12 and 13. Cooperating with the needles 12 and 13 are the thread laying fingers 54 and 55. These thread laying fingers 54 and 55 are mounted in an arm 61 carried by a short shaft which in turn is mounted in a bearing E, and said arm swings about a center 62 which is the center of the bearing E. At the upper end of the shaft carrying the arm 61, there is an arm which is connected to the link 65, and the link 65 is in turn connected to a lever arm 67. This lever arm 67 carries a roller 69 running in a cam groove 70 in a cam drum 71. This cam drum is driven by suitable gearing from the main shaft 11. The parts so far described are all shown in detail in the Thompson patent, and further description is not thought necessary. The needle bar 6 is mounted to reciprocate in a needle gate 80 which in turn is mounted to swing about a vertical axis on the needle head 4. Attached to this gate is an arm 81 and the arm 81 is connected to a rock lever 82 which carries a roller 83 running in a cam groove 84. Through this cam groove which is rotated by the main shaft the needle bar is vibrated laterally. This structure is shown and described in de-

tail in the patent to Thompson above referred to.

A small bearing block A is secured to the head 4 of the sewing machine by a screw B. This bearing block A has a rib and groove connection C with the head of the machine. This bearing block A is provided with a curved bearing surface D which is slightly eccentric to the axis of the needle bar carrying the needles 12 and 13. The bearing E is carried by a support S. This support has a rib F adapted to engage a groove in the bearing block A. The support S is provided with an elongated slot H, and a screw G passing through said slot is threaded into the bearing block A. When this screw G is loosened, the support S can be shifted on the curved surface of the bearing block A, and secured in different adjusted positions.

The thread laying finger 54 is provided with a suitable thread eye 57, while the thread laying finger 55, which is immediately below the thread laying finger 54, is likewise provided with a thread eye which is directly beneath the thread eye 57. The thread laying finger 54 is provided with suitable thread guides through which the thread Q passes. This is one of the edge forming threads. The thread laying finger 55 has suitable thread guides for the edge forming thread Q'. These threads Q and Q' pass through thread eyes M in the thread controller. Mounted on the support S which carries the thread laying fingers is a sleeve bearing J. Said bearing is secured to the support by a screw K. A wire extends through the guide bushing L in the sleeve J, and this wire carries the thread eye M. Said wire is secured to the bushing, and the bushing has a limited movement in the sleeve J. A spring P normally forces the bushing outwardly and thus moves the thread eyes M to their extreme outer position. Said bushing is provided with a groove O and a screw N carried by the sleeve J extends into this groove O and thus limits the movements of the thread eyes. The needle threads are illustrated in the drawings at R and R'. When the thread laying fingers move forward, the threads Q and Q' passing through the thread eyes M will move the thread eyes forward, compressing the spring P. This gives up sufficient thread for the laying of the edging threads, and while the thread fingers are at the forward end of their stroke, the needle 12 will secure the edging thread to the fabric. On the retracting movement of the thread laying fingers, the spring P will move the thread eyes M, and thus take up the thread. These thread eyes give up thread to the thread laying fingers, and take care of the slack formed by the retracting movement of said fingers. They also aid in the supplying of the thread for the forming of the edging.

- The spring allows the thread eyes to yield under a strain on the threads and thus the breaking of the needle threads is avoided. As shown in full lines, in Fig. 9, the needles 5 are set a distance apart indicated by the line Ia. When the machine is changed to a different width of tape, it may be desirable to set the needles a distance apart indicated by IIa as shown in Fig. 9. With this setting 10 of the needles, the thread laying fingers 54 and 55 should be improperly set so as to co-operate with both needles. Applicant's improvement enables the path of movement of the thread fingers 54 and 55 to be shifted. 15 This is accomplished by loosening the screw G and shifting the support S which carries the bearing E in which the thread fingers oscillate. By thus shifting the support, the center of oscillation 62 of the thread fingers 20 can be shifted as indicated in Figures 6 and 9. When the bearing E is set in the position indicated in full lines in Fig. 9, the distance between the center line of the needles indicated by Ic and the center line of the 25 eye is indicated by X in Fig. 9. This distance between the thread laying fingers and the needles should be maintained for all settings of the needles, and the shifting of the support S from the position I indicated in 30 Fig. 9, to the position II accomplishes this result. In other words, when the needles are set for a different width tape, the support S for the thread laying fingers is shifted, so that the path of movement of the 35 thread eyes of the thread laying fingers relative to the center line of the needles is substantially the same. Inasmuch as the supporting sleeve J for the thread eyes M is mounted on the support S, it will be shifted 40 with the support, and therefore, the thread eyes will always maintain the same operative relation to the thread fingers for the various settings thereof.
- It is obvious that minor changes in the 45 details of construction and arrangement of the parts may be made without departing from the spirit of the invention as set forth in the appended claims.
- Having thus described the invention, what 50 I claim as new and desire to secure by Letters Patent, is—
1. A sewing machine including in combination, oscillating thread laying fingers for forming edging loops, stitch forming mechanism including a pair of needles for securing the edging loops to a body material, means for oscillating said thread laying fingers, and means for shifting the center of oscillation of said thread laying fingers.
  2. A sewing machine including in combination, oscillating thread laying fingers for forming edging loops, stitch forming mechanism including a pair of needles for
- securing the edging loops to a body material, means for oscillating said thread laying fingers, means for shifting the center of oscillation of said thread laying fingers, a yielding thread controlling device for the edging threads shiftable with the thread laying fingers so that when said thread laying fingers are re-positioned as to their center of oscillation, the thread controlling device maintains its same relative position to the thread laying devices. 65
3. A sewing machine including in combination thread laying fingers for forming edging loops, stitch forming mechanism including a pair of needles, means for supporting said thread laying fingers, means for oscillating the thread laying fingers on the support, means for adjusting the support on which said thread laying fingers oscillate so as to shift the path of oscillation of the thread laying fingers relative to the needles, whereby said thread laying fingers 70 may be positioned so as to oscillate in a path at a predetermined distance from the needles. 75
4. A sewing machine including in combination thread laying fingers for forming edging loops, stitch forming mechanism including a pair of needles, means for supporting said thread laying fingers, means for oscillating the thread laying fingers on the support, means for adjusting the support 80 on which said thread laying fingers oscillate so as to shift the path of oscillation of the thread laying fingers relative to the needles, whereby said thread laying fingers 85 may be positioned so as to oscillate in a path at a predetermined distance from the needles. 90
5. A sewing machine including in combination, thread laying fingers arranged one above the other for laying edging threads in loops, a pair of needles, means for vibrating said needles, a support on which the thread laying fingers are mounted for oscillation, a bracket to which said support is adjustably attached whereby said support 95 may be shifted in a plane at right angles to the axis of oscillation of the thread laying fingers for changing the path of oscillation of the thread laying fingers relative to the needles, and means for securing said support on 100 which said thread laying fingers oscillate. 105
6. A sewing machine including in combination, an overhanging arm, a needle bar mounted in said overhanging arm, a pair of needles carried by said needle bar, a bracket secured to said overhanging arm, a support mounted on said bracket and adapted to be 110 adjusted thereon in a plane at right angles 115
- 120
- 125

to the path of reciprocation of the needle bar, a supporting arm pivotally mounted on said support, a thread finger carried by said arm, means for oscillating said arm on said support, and a thread controlling device for the thread of the thread laying finger mounted on the support for said arm and shiftable therewith.

7. A sewing machine including in combination, oscillating thread laying fingers for forming edging loops, stitch forming mechanism including a pair of needles for securing the edging loops to a body material, means for oscillating said thread laying fingers, and means for shifting the center of oscillation of said thread laying fingers, thread eyes for the threads of the thread laying fingers and means for permitting the movement of said eyes so as to supply thread to said fingers on the forward movement, and for moving said eyes so as to take up

the slack thread on the backward movement of said fingers.

8. A sewing machine including in combination, oscillating thread laying fingers for forming edging loops, stitch forming mechanism including a pair of needles for securing the edging loops to a body material, means for oscillating said thread laying fingers, means for shifting the center of oscillation of said thread laying fingers, thread eyes for the threads of the thread laying fingers, means for permitting the movement of said eyes so as to supply thread to said fingers on the forward movement and for moving said eyes so as to take up the slack thread on the backward movement of said fingers, and means for yieldingly supporting said thread eyes.

In testimony whereof, I affix my signature.

KARL MAIER.
